UNITED STATES PATENT OFFICE.

CHARLES DELAYGUE, OF PARIS, FRANCE.

REFRIGERATING APPARATUS.

Original application filed March 25, 1924, Serial No. 701,756, and in France November 24, 1923. Divided and this application filed September 22, 1925. Serial No. 57,982.

This invention relates to refrigerating apparatus of the reversing-absorption type intended for the production of cold for domestic use. The invention more particularly concerns the type of domestic refrigerating apparatus described in the specification of my co-pending application No. 701,756 filed March 25, 1924, and of which this case is a division.

10 In the specification of the application above referred to there is described apparatus comprising a generator-absorber, a condenser-evaporator, an inverted V-shaped gas return conduit extending from the top of 15 the condenser to the bottom of the generator-absorber and a gas outlet pipe extending vertically from the upper part of the generator-absorber to the said return conduit and opening thereinto at a point in advance 20 of the condenser evaporator; and the invention of the aforementioned specification is characterized by the application to such apparatus of baffles for separating out and returning to the generator-absorber any 25 aqueous vapours which may accompany the ammonia gas passing over said baffles being positioned in the gas outlet pipe between the generator-absorber and the return conduit.

30 The domestic refrigerating apparatus of the present invention comprises a generator-absorber, a condenser-evaporator, a gas conduit which extends vertically from the top of said generator-absorber, then bends 35 downwards, then forms a rectifying coil and finally returns to the generator-absorber passing to the bottom thereof, a branch extension between the end of said coil and the condenser-evaporator, and a siphon by-pass 40 so arranged that water particles separated out in said coil are returned directly to the generator-absorber by way of said by-pass.

In order that the present invention may be fully understood and readily carried into 45 effect, an example thereof will now be described with reference to and illustrated in the accompanying drawing, in which the single figure shown is a side elevation of the apparatus.

50 The apparatus shown in the drawing comprises a generator-absorber A, a condenser-evaporator G, a gas outlet pipe T and a gas return conduit R, C which extends from the upper part of the condenser G to the bottom of the generator A.

According to the present invention, a coil B is provided in the gas outlet pipe and a siphon by-pass D is arranged in order to permit condensed vapour to pass directly into the return pipe R and then back into 60 the generator A.

The liquid which contains the dissolved gas is contained in the generator A, and under the action of heat the gas is delivered through a system of check valves S (either 65 simple or multiple, with flat valves or balls) placed in the boiler and thence through the outlet pipe T which as shown rises vertically at first and then inclines slightly below the horizontal and forms the coil B. 70 The outer end of the coil B opens into the return pipe R which is completed by the pipe C which leads straight to the condenser-evaporator G. As will be seen in the drawing, the pipe R passes at R' down to the 75 bottom of the generator. The whole height of the liquid therefore opposes the return or the escape of the gas that way when heat is applied. On the contrary the pipe T remains near the surface of the liquid at T'. 80 The bend or elbow T' is designed to avoid any chance of the liquid running into the pipe T when the apparatus is worked wrongly when it would be made to oscillate, and also any projection of the solvent liquid 85 into the pipe T in case of tumultuous ebullition. The hot gas which escapes through the pipe T always carries away with it small particles of the solvent liquid. These small drops separate out in the descending 90 portion of the tube T and collect at the bottom of the coil B. This liquid will be diverted into the pipe R by the fine siphon D, and will trickle into this pipe and return thence to the generator. The pipe C opens 95 into the pipe R with an internal lip or guard which prevents any of the liquids from passing into the condenser. The gas will therefore arrive in the condenser dry.

The condenser may be of any desired 100 form, for example hollow cylindrical interior for the production of blocks of ice and of large capacity in height for the purpose of ensuring efficient and rapid evaporation, being narrow at the bottom for prolonging the cooling action until the whole 105 of the liquefied gas is exhausted.

When evaporation is taking place in the condenser, the gas issuing from the vessel G will be afforded an easy path through the 110

pipe C and the pipe R and will be reabsorbed totally by bubbling at R' into the solvent liquid.

The dimensions of the apparatus may be 5 as desired but it will be understood that the capacity of the apparatus is such as is suitable for domestic use.

I am aware that in other types of refrigerating apparatus of a complex nature it is old 10 to form the gas outlet pipe to comprise a coil; also that it is old to form in the gas outlet pipe a water trap with a by-pass back to the generator; and I wish it to be understood that I do not claim herein such 15 prior apparatus. The present invention concerns solely domestic apparatus of the type described and claimed in my specification No. 701,756 and consists in the novel combination of parts set forth in the ap- 20 pended statement of claim.

Having now particularly described and ascertained the nature of my said invention and in what manner the same is to be performed, I declare that what I claim is:—

Domestic refrigerating apparatus comprising a generator-absorber, a condenser-evaporator, a gas conduit extending upwardly from the top of the generator absorber, then laterally and back to the generator absorber, said conduit terminating adjacent 30 the bottom of the same and being formed intermediate its length with a coil, a branch extension between the end of said coil and the condenser-evaporator, and a siphon by-pass extending from the lower portion of 35 the convolution of said coil to a point between the branch extension and the generator absorber.

In testimony whereof I affix my signature.
CHARLES DELAYGUE.
